UNITED STATES PATENT OFFICE.

JESSE W. CROUSE AND WILLIAM J. BARNETT, JR., OF PHILADELPHIA, PENNSYLVANIA.

HAND-STAMP.

No. 888,593.

Specification of Letters Patent.

Patented May 26, 1908.

Application filed April 11, 1907. Serial No. 367,616.

To all whom it may concern:

Be it known that we, JESSE W. CROUSE and WILLIAM J. BARNETT, Jr., citizens of the United States, and residents of Philadelphia, in the county of Philadelphia and State of Pennsylvania, have invented certain new and useful Improvements in Hand-Stamps, of which the following is a full, clear, and exact description, such as will enable those skilled in the art to which it appertains to make and use the same, reference being had to the accompanying drawings, forming part of this specification.

The invention relates to that class of hand stamps which are provided with dating mechanism and in which the ink is supplied to the impression mechanism by a traveling ribbon. It consists in the novel construction, combination and arrangement of parts, such as will be hereinafter fully described, pointed out in the appended claims and illustrated in the accompanying drawings.

In the drawings, in which similar reference characters designate corresponding parts, Figure 1 is a longitudinal sectional view of a hand stamp embodying the invention. Fig. 2 is a horizontal sectional view. Fig. 3 is a front elevation with the front door removed. Fig. 4 is a rear elevation, partly in section, with the rear door removed. Fig. 5 is a detail view showing one of the ribbon winding mechanisms. Fig. 6 is a similar view showing the other ribbon winding mechanism.

The main part of the casing in which the operative parts are mounted may be of any suitable construction. In the forward part of the top of the casing is a seat in which is placed the impression plate 1 having on its upper surface the characters to print the permanent part of the imprint. The forward end of the seat is open to permit the insertion and withdrawal of the plate. The latter is held in place by the spring bail 2 hinged to the casing and operating to engage the hooked end of the lug 3 on the under side of the plate. When the bail is disengaged from the lug the plate can be readily removed from the seat.

In the casing beneath the impression plate 1 is journaled the arbor 4 carrying the independently rotatable dies 5, 6, 7. On the peripheries of the dies are characters to designate the years, months and days. The peripheries of the dies project through a slot in the impression plate located with regard

to the characters thereon for printing the permanent part of the imprint. The die 5, which is rotatable on the arbor 4, is adjusted by the wheel 8 on the outer end of the shaft 9 journaled in the casing. On the inner end of the shaft is the gear 10 meshing with the gear 11 fast on the side of the die 5. By turning the wheel 8 the die 5 can be adjusted so that the desired characters on its periphery will project through the slot in the impression plate. On the shaft 9 outside of the casing is the indicating dial 12 having characters to correspond with those on the periphery of the die 5. As the characters on the die are not visible the indicating dial facilitates the adjustment of the die so as to present the desired characters in the impression surface. The die 6 is fast on the arbor 4 and by turning the latter by means of the wheel 13 the die can be adjusted to present the desired characters on its periphery to the impression surface. The adjustment of the die 6 is facilitated by the indicating dial 14 fast on the arbor 4 outside of the casing. The die 7, which is also journaled on the arbor 4, is adjusted by the wheel 15 on the shaft 16 journaled in the casing. On the inner end of the shaft 16 is the gear 17 meshing with the gear 18 fast to the die 7. For the latter the indicating dial 19 is mounted on the shaft 16 outside of the casing to aid in its adjustment. The dies are held against accidental displacement by the spring-pressed detents 20. In regard to the dies 5 and 7 the detents engage radial sockets on their outer faces; as to the die 6, its controlling detent engages sockets in the periphery of the indicating dial 14. By means of their respective operating mechanisms any one or all of the dies can be adjusted to present the desired date in the impression surface. It is to be observed that the casing adjacent to the operative shafts and arbor of the dies is recessed so that the projecting ends will be inside of the general configuration of the casing and thereby protected against injury.

Coöoperating with the impression surface to form the imprint is the hammer 21 carried by the arm 22 pivoted to the rear end of the casing. The hammer is normally held in a raised position by the spring 23 interposed between the arm 22 and the top of the casing. In the face of the hammer is a seat in which is held the platen 24 by the screw 25. On the top of the hammer is the cushion 26

of cork or other suitable material held in place by the retaining ring 27 screwed onto the crown of the hammer. When the hammer is pressed downwardly against the action of the spring 23 the platen 24 presses the article placed beneath the same onto the impression surface formed by the plate 1 and the dies 5, 6, 7 to form the imprint.

Ink is supplied for the imprint by the ribbon 28 passing over the impression surface beneath the hammer. Preliminary to its insertion in the machine the ribbon is wound on a spool having a hollow rectangular core adapted to fit the arm 29. By means of the union joint 30 the arm 29 is hinged to the spindle 31 journaled in the casing. Through this connection the arm can be turned down through the opening in the bottom of the casing so that the spool can be placed on the same. As the main part of the arm is rectangular and fits the core of the spool the latter is non-rotatable thereon. The free end of the arm is rounded and when in place is journaled in the annular lug 32 projecting inwardly from the side of the casing. The lower side of this lug is open to admit the end of the arm and the latter is held in the lug by the thimble 33 screwed onto the lug. The ribbon leaves the arm 29 and passes around the slack-adjusting roll 34 carried by the yoke 35 journaled at its ends in the casing. A spring 36 presses the yoke so that the roll exerts a tension on the ribbon. The ribbon then passes over the impression surface formed by the plate 1 and the dies 5, 6, 7 and leads through the slot 37 to the sleeve 38 to which its end is secured in any suitable manner. The sleeve 38 is keyed on the shaft 39 journaled in the casing.

Mechanism is provided for moving the ribbon in either direction across the impression surface. The lower end of the arm 22 projects into the casing and is connected by the wrist-pin 40 with an end of the link 41. The other end of the link is pivoted by the pin 42 with the upper end of the lever 43 journaled at its lower end on the shaft 39. On the pin 42 is the double pawl having its arms 44 and 45 extending in opposite directions. The pawl-arm 44 operates to engage the ratchet-wheel 46 loosely journaled on the shaft 39. To the side of the ratchet-wheel 46 is secured the gear 47 meshing with the gear 48 on the spindle 31. When the ratchet-wheel 46 is turned by the pawl-arm 44, through the intervening gears the arm 29 on the spindle 31 is rotated to wind the ribbon onto the spool carried by the said arm. The pawl-arm 45 operates to engage the ratchet-wheel 49 on the shaft 39. When this ratchet-wheel is turned by its pawl-arm the shaft 39 is rotated to wind the ribbon onto the sleeve 38 carried by said shaft. When the arm 22 is moved the link 41 connected with it oscillates the lever 43 and rocks the double pawl

at the upper end of the latter. The rocking of the double pawl, depending upon the engagement of either of its arms with its respective ratchet-wheel, rotates either the sleeve 38 or the arm 29 to move the ribbon 70 in one direction or the other through the machine.

Mechanism is provided for automatically operating the double pawl to cause the ribbon first to travel in one direction through the 75 machine and then to reverse the movement so that the travel will be in the opposite direction. On the shaft 39 is the gear 50 meshing with the gear 51 on the shaft 52 journaled in the rear of the casing. The shaft is screw-threaded and carries the traveler 53 threaded thereon. When the shaft is rotated in one direction and then oppositely the traveler moves back and forth across the machine. Above the shaft and parallel with 80 it is the guide-rod 54 longitudinally movable in bearings in the sides of the casing. On this guide-rod the upper end of the traveler moves. At one end of the guide-rod is the pin 55 having a loose connection with one 85 end of the bell-crank 56 pivoted to the side of the casing. The other end of the bell-crank is connected by the link 57 with the dog 58 pivoted to the casing above the double pawl. On the axis pin of the pawl is the lever 59 carrying at its upper end the weight 60. The lever extends upwardly between the arms of the dog 58 and the latter operates to move the lever and to shift the weight from one side of the pivotal point of the pawl to 90 the other side to oscillate the pawl. This movement of the pawl causes one or the other of its arms 44, 45 to engage with its respective ratchet-wheel. The weight not only aids in the throwing of the pawl, but 95 also presses the operating pawl-arm into engagement with its ratchet-wheel. The movement of the traveler 53 across the machine is limited in one direction by the pin 55 on one end of the guide-rod and in the opposite direction by the adjustable collar 61 on the other end of the guide-rod. The guide-rod is graduated so that the movement of the traveler can be regulated by adjusting the collar 61. The traveler engaging either the 100 pin 55 or the collar 61 moves the guide-rod longitudinally in its bearings to shift the pawl through the intervening mechanism.

In the front and rear of the casing are the hinged doors 62 normally held closed by the springs 63 secured to them and bearing against the casing on the opposite sides of the hinged connections. By means of these doors and the open bottom of the casing access to the operative parts within the casing 105 can be had.

The operation of the machine is as follows: It is assumed that the dies have been adjusted to present the required date in the impression surface and that the ribbon has 110

been placed in the machine and the connections made and that the double pawl has been thrown so that its arm 44 engages the ratchet-wheel 46 as shown in Fig. 1 of the drawings. The article to be stamped is placed on the impression surface above the ribbon and the hammer 21 is struck to make the imprint. When the hammer descends the lower end of the arm 22 moves to the rear and through the intervening connections the double pawl is also moved a short distance so that the arm 44 engages with the succeeding tooth of the ratchet wheel 46. When the hammer is released the spring 23 raises the arm 22 and the lower end of the latter moves forward a short distance. Through the intervening connections the pawl is rocked so as to rotate the ratchet-wheel 46. The rotation of the ratchet-wheel, through the intervening gears 47, 48, rotates the spindle 31 and the arm 29 carried by the latter winds a short length of the ribbon upon the spool carried by the arm. At each movement of the hammer this is repeated and the ribbon is gradually wound off the sleeve 38 onto the spool carried by the arm 29 so that the ribbon is fed intermittently across the impression surface. The travel of the ribbon from the sleeve 38 to the spool on the arm 29 continues until the reversing mechanism operates to change the direction of the ribbon. While the ribbon is passing from the sleeve 38 to the arm 29 the traveler 53 is moving along the guide-rod 54 from the adjustable collar 61 towards the pin 55. When the traveler strikes the pin 55, or the end of the bell-crank 56 on said pin, the guide-rod is moved longitudinally to the right. This movement of the guide-rod oscillates the bell-crank and the latter through the connecting link 57 turns on the dog 58 to the rear. The dog throws the lever 59 and the weight 60 carried by it to the rear. The lever rocks the double pawl on its axis so that the pawl-arm 44 disengages the ratchet-wheel 46 and the other pawl-arm 45 engages the ratchet wheel 49 on the shaft 39. With the pawl-arm 45 in engagement with the ratchet-wheel 49 the subsequent movements of the arm 22 through the striking of the hammer will rotate the shaft 39 to unwind the ribbon from the spool on the arm 29 and wind it on the sleeve 38. With the reversal of the ribbon the gear 50 is also reversed, which turns the screw-threaded shaft in the opposite direction. This causes the traveler 53 to change its direction and to move from the pin 55 towards the collar 61. When the traveler strikes the collar the guide-rod 54 is moved to the left and the bell-crank 56 is thereby moved to operate the dog 58 to throw the double pawl to its original position, thereby reversing the travel of the ribbon again. This is repeated until the ribbon is exhausted and needs replacing. By ad-

justing the collar 61 on the guide-rod according to the length of the ribbon the reversing mechanism can be regulated to act as the end of the ribbon is reached by either winding mechanism.

Having thus described our invention, what we claim and desire to secure by Letters Patent is,

1. In a hand-stamp, an impression mechanism comprising fixed and movable members, a ribbon for supplying ink to the impression mechanism, winding mechanisms at the ends of the ribbon, ratchet-wheels operating to drive said winding mechanisms in opposite directions, a pivoted lever oscillated by the movable member of the impression mechanism, a double pawl pivoted to the free end of said lever operating to engage either ratchet-wheel, a rotatable shaft, a traveler threaded on said shaft, and a tripping mechanism actuated by said traveler for shifting the pawl from one ratchet-wheel to the other to reverse the travel of the ribbon. 70

2. In a hand-stamp, an impression mechanism comprising fixed and movable members, a ribbon for supplying ink to the impression mechanism, winding mechanisms at the ends of the ribbon, ratchet-wheels operating to drive said winding mechanisms in opposite directions, a pivoted lever oscillated by the movable member of the impression mechanism, a double pawl pivoted to the free end of said lever operating to engage either ratchet-wheel, a shaft rotated by one of said winding mechanisms, a longitudinally movable guide-rod extending parallel with said shaft, a traveler threaded on said shaft and engaging said guide-rod operating to move the latter as it approaches the ends of the shaft, a bell-crank connected with said guide-rod, a dog connected with said bell-crank, and a weighted lever on said pawl engaged by said dog and operated by the latter to shift said pawl from one ratchet-wheel to the other to reverse the travel of the ribbon. 90

3. In a hand-stamp, an impression mechanism comprising fixed and movable members, a ribbon supplying ink to the impression mechanism, winding mechanisms at the ends of the ribbon, concentric ratchet-wheels operating to drive said winding mechanisms in opposite directions, a lever pivoted concentrically to said ratchet-wheels oscillated by the movable member of the impression mechanism, a double pawl pivoted to the free end of said lever operating to engage either ratchet-wheel, and intermittently operating mechanism for shifting said pawl from one ratchet-wheel to the other to reverse the travel of the ribbon. 105

4. In a hand-stamp, an impression mechanism comprising fixed and movable members, a ribbon for supplying ink to the impression mechanism, winding mechanisms at the ends of the ribbon, concentric ratchet-wheels 115

operating to drive said winding mechanisms in opposite directions, a lever pivoted concentrically to said ratchet-wheels, a double pawl pivoted to the free end of said lever 5 operating to engage either ratchet-wheel, a rotatable shaft, a traveler threaded on said shaft, and a tripping mechanism actuated by said traveler for shifting the pawl from one ratchet-wheel to the other to reverse the travel of the ribbon.

5. In a hand-stamp, an impression mechanism comprising fixed and movable members, a ribbon for supplying ink to the impression mechanism, winding mechanisms at the ends 15 of the ribbon, concentric ratchet-wheels operating to drive said winding mechanisms in opposite directions, a lever pivoted concentrically to said ratchet-wheels, a double pawl pivoted to the free end of said lever 20 operating to engage either ratchet-wheel, a shaft rotated by one of said winding mechanisms, a longitudinally movable guide-rod extending parallel with said shaft, a traveler threaded on said shaft and engaging said 25 guide-rod operating to move the latter as it approaches the ends of the shaft, a bell-crank connected with said guide-rod, a dog connected with said bell-crank, and a weighted lever on said pawl engaged by said 30 dog and operated by the latter to shift said pawl from one ratchet-wheel to the other to reverse the travel of the ribbon.

6. In a hand-stamp, an impression mechanism comprising fixed and movable members, a ribbon for supplying ink to the impression 35 mechanism, winding means at each end of the ribbon, a ratchet-wheel for each winding means, a pawl actuated by the movable member of the impression mechanism operating to engage either ratchet-wheel to turn 40 the latter, a shaft rotated by one of the winding mechanisms, a traveler threaded on said shaft, and tripping mechanism operated by said traveler to throw the pawl from one 45 ratchet-wheel to the other to reverse the travel of the ribbon.

7. In a hand-stamp, an impression mechanism comprising fixed and movable members, a spindle rotated by the operation of 50 the movable member of the impression mechanism, an arm hinged to said spindle to receive the ribbon spool, an annular lug having an opening to receive the free end of said arm, and a thimble turned onto said lug to hold 55 the lever therein.

8. In a hand-stamp, an impression plate provided with a slot, independently rotatable dies mounted beneath said plate and registering with said slot, a movable hammer co-operating with said impression plate and the dies, an inking ribbon leading over the impression plate and dies, winding means at each end of the ribbon, a ratchet-wheel for each winding means, a pawl operating to engage either 60 ratchet-wheel, means actuated by said ham-

mer for rocking said pawl to turn the engaged ratchet-wheel, a shaft rotated by one of the winding mechanisms, a traveler threaded on said shaft, and tripping mechanism operated by said traveler to throw the pawl from one 70 ratchet-wheel to the other to reverse the travel of the ribbon over the impression plate and dies.

9. In a hand-stamp, an impression plate provided with a slot, an arbor journaled beneath said plate, dies mounted on said arbor registering with said slot with one of said dies fast on the arbor and the others loose thereon, a rotatable shaft for each one of the loose dies, gear connections between said shafts and their respective dies, means for rotating said arbor and said shafts, indicating dials on said arbor and said shafts, a movable hammer co-operating with said impression plate and dies, an inking ribbon leading over said 80 impression plate and dies, winding means at each end of the ribbon, a ratchet-wheel for each winding means, a pawl operating to engage either ratchet-wheel, means actuated by said hammer for rocking said pawl to turn 85 the engaged ratchet-wheel, a shaft rotated by one of the winding mechanisms, a traveler threaded on said shaft, and tripping mechanism operated by said traveler to throw the pawl from one ratchet-wheel to the other to 90 reverse the travel of the ribbon over the impression plate and dies.

10. In a hand stamp, an impression mechanism, a ribbon for supplying ink to the impression mechanism, winding mechanism at each end of the ribbon, a ratchet-wheel for each winding mechanism, a pawl operating to engage either ratchet-wheel, a weighted lever on said pawl for shifting the latter from one ratchet-wheel to the other, a dog engaging 105 said lever to throw the pawl in either direction, and means actuated by one of the winding means for moving said dog.

11. In a hand stamp, an impression mechanism, a ribbon for supplying ink to the impression mechanism, winding means at each end of the ribbon, a ratchet-wheel for each winding means, a pawl operating to engage either ratchet-wheel, means for rocking said pawl to turn the engaged ratchet-wheel, a 110 shaft rotated by one of the winding mechanisms, a traveler threaded on said shaft, and tripping mechanism operated by said traveler to throw the pawl from one ratchet-wheel to the other.

12. In a hand stamp, an impression mechanism, a ribbon for supplying ink to the impression mechanism, winding mechanism at each end of the ribbon, a ratchet-wheel for each winding mechanism, a pawl operating to 115 engage either ratchet-wheel, a weighted lever on said pawl, a pivoted dog engaging said lever operating to move the same to shift the pawl from one ratchet-wheel to the other, a shaft rotated by one of the winding 120 mechanisms.

mechanisms, a longitudinally movable guide-
rod parallel with said shaft, a bell-crank con-
nected with said guide-rod and with said
dog, a traveler threaded on said shaft and
sliding on said guide-rod, and stops on said
guide-rod to engage the traveler to move the
guide-rod.

In testimony whereof we hereunto affix

our signatures in the presence of two wit-
nesses.
